UNITED STATES PATENT OFFICE.

SIDNEY H. BURNS AND CHARLES D. PERILLAT, OF NEW YORK, N. Y., ASSIGNORS TO
OVIDA COMPANY, OF NEW YORK, N. Y.

DESIGN FOR A BUST-REDUCER BRASSIÈRE.

45,287.

Specification for Design.

Patented Feb. 24, 1914.

Application filed January 6, 1914. Serial No. 810,682. Term of patent 14 years.

To all whom it may concern:

Be it known that we, SIDNEY H. BURNS, a citizen of the United States, and CHARLES D. PERILLAT, a citizen of France, both residing at the city of New York, borough of Manhattan, in the county and State of New York, have invented a new, original, and ornamental Design for Bust-Reducer Brassières, of which the following is a specification, reference being had to the accompanying drawings, forming part thereof.

Figure 1 is a front view in perspective; and Fig. 2 is a rear view, showing our new design.

We claim:

The ornamental design for a bust reducer brassière, as shown.

SIDNEY H. BURNS.

CHARLES D. PERILLAT.

Witnesses:

F. L. WHEAT,

H. GOODRICH.
